TELEPHONE SYSTEM

Owen Avis Pearce, Heswall, Wirral, England, assignor to Associated Telephone & Telegraph Company, Chicago, Ill., a corporation of Delaware

Application May 3, 1941, Serial No. 391,643
In Great Britain June 22, 1940

16 Claims. (Cl. 179—17)

The present invention relates to telephone systems and is more particularly concerned with systems in which a group of subscribers is served for both incoming and outgoing calls by a single two-conductor line extending to the exchange. The chief object of the invention is to provide an improved multi-party line system of this type in which improved arrangements are made to maintain and to supervise the service to the group of subscribers involved.

According to one feature of the invention, in a telephone system including party lines arranged so that only one party at a time can connect his equipment to the line, each subscriber's equipment includes a device adapted to be operated in response to a controlling action at the exchange to disconnect the said equipment from the line.

According to another feature of the invention, in a telephone system including party lines arranged so that the connection of any subscriber's equipment to the line for either an incoming or an outgoing call is dependent upon the transmission of impulses from the exchange, the impulses also serve to effect the stepping of a switch at the exchange the circuit for bringing this switch to rest when the required number of impulses have been transmitted extending over a wiper of the switch to enable a portion to be individual to the various stations so that service to particular stations may be denied by interrupting the corresponding individual portion.

According to a further feature of the invention, in a telephone system including party lines arranged so that the connection of any subscriber's equipment to the line for either an incoming or an outgoing call is dependent upon the transmission of impulses from the exchange, if the line is looped due to a fault, the impulse responsive switches at the substations are set to a characteristic position in which no station is connected up and a switch in the exchange which steps in synchronism with the substation switches is set to a corresponding position in which it initiates the giving of an alarm.

The invention will be better understood from the following description of one method of carrying it into effect, reference being had to the accompanying drawings comprising Figs. 1-3. These should be arranged side by side with Fig. 1 on the left to form a circuit diagram of the switching unit required at the main exchange per party line group and of the equipment required at the station of one subscriber in the group.

It will be seen that one two-conductor line ex-

tending from the exchange is provided per group of subscribers, the apparatus required individual to each subscriber in the group being connected across the line as shown in Fig. 3 which discloses the equipment of only one of the subscribers, for instance subscriber No. 4.

Each party line group is assumed to comprise up to ten subscribers, each of which requires apparatus including two neon tube gas discharge devices NTA and NTB, two step-by-step electromagnetically-operated 12-position switches F and C and a relay PGR which is provided with a mechanical latch so that it will lock in its operated position. Assuming the main exchange is automatic, each subscriber will also be provided with an automatic telephone instrument the circuit of which is also shown in Fig. 3.

At the main exchange each party line group is provided with a switching unit, the circuits of 20 which are shown in Figs. 1 and 2, which unit is introduced between the party line and the usual line and cut-off relay assembly and includes a 25-position reverse-drive electromagnetically-operated stepping switch which serves to count 25 or control the impulses transmitted on calls between the main exchange and the group of subscribers.

It will be appreciated that in addition to the facilities already mentioned, the party line system to be described is suitable for use in connection with either a manual or an automatic exchange, provides secrecy of communication and quality of transmission substantially equal to that of ordinary individual line subscribers, and gives individual metering of outgoing calls. Provision is also made for local intercommunication between the subscribers of a group. The general arrangements are similar to those of the system disclosed in United States Patent No. 40,2,180,963.

Before consideration is given to the circuit operations consequent on the initiation or reception of a call by a party line subscriber, reference will be made to the switches F and C which 45 are provided at the station of each subscriber in the group. Of the twelve positions provided thereon, the first is the home position, the second is utilised under line fault conditions as will be seen later and of the other ten positions a different position is allocated to each subscriber. Two cams are mounted on the driving shaft of each switch, one of which serves to operate off-normal springs when the switch steps from the home position, while the other cam is arranged 50 to operate other springs in the particular posi-

tion of the switch characteristic of the subscriber concerned. Thus the switches associated with No. 1 subscriber will operate these springs in position 3 only, while the switches associated with No. 2 subscriber will operate these springs in position 4 only, and so on up to position 12 for No. 8 subscriber.

When one of the subscribers initiates a call by removing his receiver, the switch hook contacts SH1 complete a loop across the negative and positive leads to the main exchange. A circuit is then completed from earth, wiper S1, Fig. 2 in position 1, armatures on3 and ic3, left-hand high resistance winding of relay ST, armatures rf1, sr3, pg2, ic2, pr3 and ct4, negative conductor of the party line, armature pgr1 in the calling station, off-normal contacts F(N)2 of switch F, off-normal contacts C(N)2 of switch C, rectifier MRE in a conductive direction, winding of relay PGR, contacts SH1, resistance 10, positive line, armatures ct5, pr1, sr4, rf2, pg3, right-hand winding of relay RF to battery. Only relay ST operates in this circuit and locks up over its make first armature st1 and its right-hand winding, and at armature st2 operates relay ON, at armature st4 busies the line to incoming calls and at armature st3, Fig. 1, applies earth to common lead 13 in order to start up a common pulse machine or pulsing relay, contacts of which will periodically loop the conductors 14 and 15, Fig. 2, at a rate of the order of three pulses per second. The first looping of leads 14 and 15 operates relay PGA from earth connected over armatures ct6, sz2, sr1, on2, on1, and st2. This relay thereupon at armature pga1 prepares a circuit for relay PG which is short-circuited at this stage and at armature pga3 maintains an earth on start lead 13 independently of relay ST. When the connection between leads 14 and 15 is opened, the short-circuit is removed from relay PG which thereupon operates in series with relay PGA which holds. Thereupon at armature pgl relay PR is connected up to the pulse lead 14, at armature pg2, Fig. 1, the earthed winding of relay ST previously connected to the negative line is replaced by the upper battery-connected winding of relay SZ and at armature pg3, Fig. 2, the winding of relay RF previously connected to the positive line is replaced by an earth potential. The effect of this reversal is that rectifier MRE in the calling station will now be nonconductive and hence relay SZ cannot yet operate.

On the next closure of the impulse contacts, relay PR operates and at armature pr1 applies a high potential of the order of 100 volts negative to earth over common lead 12 and armatures cr2, pr1 and ct5 to the positive line, at armature pr2 completes an energising circuit for the magnet SM of the switch S, and at armature pr3, Fig. 1, disconnects relay SZ from the negative line.

On the next opening of the pulsing contacts, relay PR releases and disconnects the high voltage pulse circuit and the circuit to the magnet SM whereupon the wipers of switch S are advanced to position 2. Succeeding pulses operate on relay PR in the manner described and high potential pulses which are counted by switch S are transmitted to all the party line subscribers' equipments in parallel.

In response to each pulse the neon tube NTA associated with each station in the group is caused to strike since the rectifier MRC in series therewith is in a conductive direction and current thereupon flows through the winding of

each switch F which responds, the rectifier MRD in parallel therewith being non-conductive for current in this direction.

In response to the first pulse received, each F switch advances from the home position 1 to position 2 in which position the off-normal springs are operated and at contacts F(N)1 remove rectifier MRD from across the magnet winding, while contacts F(N)2 disconnect the calling loop from across the line. At the same time contacts F(N)2 of other subscribers' switches prevent them looping the line if they attempt to originate a call.

In response to the second pulse the F switches are stepped to position 3 whereupon the contacts F1 and F2 on the switch associated with subscriber No. 1 are operated. Assuming that this subscriber has not originated the call, no loop by way of his instrument will be connected across the line since his switch hook contacts are not operated and therefore the transmission of setting pulses from the exchange will not be stopped.

If however subscriber No. 4 has originated the call, when all F switches are stepped to position 6 on receipt of the fifth pulse from the main exchange, a loop will be connected across the line by way of contacts F2 of the switch associated with subscriber No. 4, impulse springs of dial switch ID, telephone instrument, contacts F1, winding of relay PGR, contacts SH1, resistance 10 to positive line. On the release of relay PR at the end of the fifth pulse, relay SZ is reconnected to the negative line by armature pr3 and it thereupon operates over the loop to the earth potential connected to the positive line over armatures ct5, pr1, sr4, rf2 and pg3. Relay PGR still does not operate. Relay SZ at armature sz1 completes a locking circuit for itself over wiper and bank S5 to battery connected to the negative line via the winding of the line relay associated with the party line group, which relay now operates and at armature sz2, Fig. 2, disconnects the earth feed to the impulsing circuit for relay PR and releases relays PGA and PG thereby stopping the transmission of pulses from the exchange to the party line. Relay ST will have released when the S switch advanced from the home position 1, but relay ON remains held over the wiper and bank S1.

It will be understood that although all the subscribers' F switches have been set in position 6, since only the F switch associated with No. 4 subscriber is arranged to operate its contacts F1 and F2 in this position, only the telephone instrument of No. 4 subscriber in the group will be bridged across the line. In the main exchange the switch S which has been stepped in synchronism with the switches F will also be set in position 6 and in a manner to be described serves to effect individual metering of outgoing calls on the automatic main exchange. In the case of a manual exchange it serves to indicate to the operator which subscriber in the group has originated the call.

For the purpose of the description the automatic main exchange is further assumed to be of a known type employing individual line switches and booster battery metering. Accordingly when relay SZ locks in series with the line relay, the operation of the latter will cause the rotary line switch to hunt for an idle first selector. Relay CT is connected across leads M and M1 in parallel with the cut-off relay, lead M1 extending to the battery side of the cut-off relay, and hence when this relay operates when an idle

first selector is found, relay CT is also operated. The cut-off relay and relay CT thereupon extend the negative and positive party line leads through to the first selector in preparation for receiving dialled digits in accordance with the wanted number. Relay SZ is disconnected from the negative line at armature $ct3$ and releases, and the impulse receiving relay in the first selector is now operated from the calling party's loop. At armature $ct2$ battery is connected up over wiper and bank S3 to the particular meter MTR1—MTR10 associated with the calling party line subscriber, the meter being in this case meter MTR4 which is selected by wiper S3 in position 6. This meter is now in readiness for being operated by booster battery metering potential which will be extended thereto over the M lead when the wanted party subsequently answers after the dialled up connection has been extended through. Conversation now proceeds and it will be noted that although relay PGR is in circuit with the conversational path, a low impedance to speech currents is offered by the condenser QB bridged across it.

At the end of conversation when the calling subscriber hangs up, the earth which holds the cut-off relay and relay CT is removed and these two relays now release. Relay CT at armatures $ct4$ and $ct5$ prepares for the sending out of further high potential pulses to the party line and at armature $ct6$ re-completes the pulsing circuit for relay PR. Relays PGA and PG are operated as before and relay PR is then pulsed to extend further high potential negative pulses to the positive line and at the same time to extend pulses to the magnet SM of switch S.

In response to the application of the high potential negative pulses, the F switches at the various party line stations are stepped in synchronism until they again reach the home position 1 when the contacts F(N)1 and F(N)2 will be restored to normal. Rectifier MRD will now be bridged across the winding of each F switch magnet and serves as a short-circuit during the break period between pulses, thereby holding the magnet operated to prevent the switches from being stepped past this position. The total number of pulses transmitted is at least equal to the maximum number required to home the F switches from any position, and sending out of these pulses is terminated when the wiper S1 reaches either of the homing positions 13 or 1 according to whether the switch is working over the first or second half of the bank. Relays ON, PGA, PG and PR now restore and the various F switch magnets of the parties also restore and all subscribers' equipments and the main exchange equipment is now normal in readiness for further calls.

Considering now an incoming call to one of the group subscribers, when the final selector selects the desired party, earth is extended from the switching relay therein over a particular one of the private conductors P1—P0, Fig. 2 in the final selector multiple FSM according to the particular party line subscriber being called, and this earth extends via bank and wiper S2 to operate relay IC.

The arrangement for the individual extension of the P conductors 1—0 associated with the wanted group via jack links IL1 to IL10 to relay IC is provided to enable any subscriber to be barred incoming service from the main exchange if this be so required, and this can be effected by removal of the relevant link. The same re-

marks apply in connection with outgoing calls where by removal of any one of the links OL1 to OL10 outgoing service can be denied to the corresponding parties since if a subscriber with barred outgoing service facilities attempts to originate an outgoing call, no circuit can be completed for relay SZ to stop transmission of pulses when sufficient have been sent to set the F switches on to a position corresponding to the particular party involved. In these circumstances transmission is automatically stopped by the release of relay ON when the S switch reaches its home position at which time the F switches will again have reached their normal positions.

Returning to the operation of relay IC in response to an incoming call, this relay at armature $ic1$ locks independently of wiper S2, disconnects the normal connection of the left-hand winding of relay ST to the line at armature $ic2$, completes an operating circuit for relay ST by way of its right-hand winding at armature $ic3$, and at armature $ic4$ applies earth to the P lead extending to the line switch circuit so as to operate the cut-off relay therein and so prevent the line relay from being energised and initiating the operation of the line switch. Relay IC also at armature $ic5$ prepares a circuit for relay CR and at armature $ic6$ disconnects any circuit for the meters MTR1—MTR10. Relay ST as before locks over its armature $st1$, operates relay ON over its armature $st2$ and at armature $st3$ applies earth to the pulse machine start lead 13. Relay ON connects earth over armatures $st2$, $on1$, $on2$, and $ic5$ to operate relay CR which locks independently of relay IC at its armature $cr1$. Relay CR also at armature $cr2$ connects up over common lead 11 a source of high potential positive to earth to the armature $pr1$ and at armature $cr3$ connects up the lower winding of relay SZ to the positive party line conductor. Relay ON also at its armatures $on1$ and $on2$ extends earth to the pulsing circuit and relays PGA and PG operate as before, while relay PR is impulsed from the pulsing contacts connected to leads 14 and 15. At armature $pr1$ high potential positive pulses are now applied to the positive line, while at armature $pr2$ the switch magnet SM is operated in synchronism and the number of pulses applied to line will be adjusted as will be seen later in accordance with the particular subscriber required.

At the various stations the rectifier MRC will now be non-conductive and rectifier MRB conductive to these pulses so that the C switches will now respond to the high potential pulses applied.

Considering now the impulse train in detail, the first pulse transmitted steps both the S and C switches to position 2, while the next ten pulses step the C switches to the effective positions 3—12. The number of pulses transmitted is determined by wiper and bank S4, Fig. 1, in accordance with the particular subscriber being called. For instance, if No. 4 subscriber is being called, after a total of five pulses have been transmitted when the S and C switches will occupy position 6, wiper S4 will encounter battery potential from the ringing return battery in the final selector which connects with contact 6 in the S4 bank via No. 4 positive conductor of the party line group in the final selector multiple. Relay SZ will thereupon operate over its lower winding and will stop the transmission of pulses as previously described. Relay SZ also operates relay CT as before since the cut-off relay is operated and relay CT at ar-

matures $ct4$ and $ct5$ connects No. 4 party line positive conductor in the final selector multiple and the negative conductor common to the party line group in the final selector multiple through to the party line whereupon ringing current is extended via the final selector ring trip relay and out over the negative conductor of the party line. Meanwhile at the station of the wanted subscriber No. 4, contacts $C1$ and $C2$ of the switch C will have been operated on the positioning of this switch to position 6 and the earthed bell B of this subscriber is connected by way of normal contacts $SH2$, condenser QA and contacts $C2$ to the negative line, so that this bell will ring.

When subscriber No. 4 removes his receiver, contacts $SH1$ and $SH2$ operate to disconnect the bell and to connect a loop via the telephone instrument across the line, thereby tripping the ringing. Conversation now proceeds.

At the conclusion of the conversation when the calling party hangs up, earth is removed from the final selector P lead thereby releasing relay IC which in turn releases the cut-off relay in the line switch circuit and also relay CT . Relay SZ is also released on the release of the final selector, and earth will therefore be extended over wiper and bank SI and armatures $on2$, $sr1$, $sz2$ and $ct6$ to start up the pulsing circuit relays once again.

A plurality of positive pulses is now transmitted over the positive line to home the C switches and the S switch is also homed and controls the number of homing pulses sent out in the manner described previously in connection with the F switches, after which all equipment is restored to normal in readiness for subsequent calls.

Should a party line subscriber desire to call another subscriber on the same line, he first calls the exchange in the usual manner, whereupon all F switches are set to a position in accordance with the number of the particular subscriber calling, and the calling subscriber is connected up to a first selector. The dialling of the number of another subscriber on the same line then causes the call to be extended to a revertive calling switch which is suitably set by further dialling. The calling subscriber now hangs up and it will be understood that the revertive calling equipment now transmits the required number of positive pulses over the positive line to step all C switches to the position corresponding to the wanted party, the transmission being effected in a similar manner to that employed by the switching unit in the case of an incoming call to the party line. At the end of the positive pulse train, the C switch associated with the wanted party closes its contacts $C1$ and $C2$ and thereby connects his earthed bell to the negative line. It will be appreciated that the F switch associated with the calling subscriber will also have operated contacts $F1$ and $F2$ and since his receiver is already restored, his bell also will be connected to the negative line. On the application of ringing current, the bells of both the calling and called subscribers will thus be rung in parallel and when they reply, their telephones will be connected in parallel to the main exchange and conversation may proceed.

It will be noted that a resistance 10 is included in the conversational circuit of each of the parties, and it will be understood that these resistances are adjusted so that the loop resistance offered by all parties approximates to 600 ohms thereby ensuring that currents through the

transmitters of the two parties under revertive call conditions will be substantially equal.

On the completion of a conversation a series of high voltage positive pulses are first of all transmitted to line from the revertive relay set to home the C switches. The counting switch in the revertive relay set corresponding to the switch S in the switching unit shown on reaching its normal position causes the revertive relay set to drop out of the connection. Relay CT is thereupon released to initiate the sending out of a series of negative pulses to home the F switches in the same manner as described in connection with an outgoing call originated by a party line subscriber.

In case a party line subscriber should remove his receiver but omit to dial, the selector taken into use originates an alarm via suitable delayed alarm equipment. Arrangements are provided whereby the faulty station in question may be isolated or locked out from the common line in order that this line may be restored to the service of the other stations thereon. For this purpose a key designated KPR is provided in the switching unit in the exchange and on being momentarily operated clears the faulty subscriber from the common line in the following manner. At contacts $KPR1$, Fig. 2, relay SR is operated, and this relay at armature $sr2$, Fig. 1, releases relay CT to clear the connection set up to the main exchange first selector.

On the release of the key, relay SR commences to release slowly, and during its release time high voltage positive to earth is fed over common lead 11 , key contacts $KPR2$ and armatures $sr3$, $pg2$, $ic2$, $pr3$ and $ct4$ on to the negative line, while an earth potential is fed over contacts $KPR1$ and armatures $sr4$, $pr1$ and $ct5$ on to the positive line. At the faulty substation the so-called "permanent glow" relay PGR is connected across the line by way of resistance 10 , switch hook contacts $SH1$, winding of relay PGR , F switch contacts $F1$, telephone instrument, F switch contacts $F2$ to the negative line and relay PGR is thereupon operated. The neon tubes NTA and NTB do not tend to flash under this condition since they are short-circuited by the earth connected to the positive line at the main exchange. On operating, relay PGR mechanically locks in the operated position by means of a suitable latching arrangement and at armature $pg1$ opens the "start" loop circuit.

On the release of relay SR the high voltage positive pulse source and the earth return are disconnected from the line and at armature $sr1$ an operating circuit is recompleted for relays PGA and PG and for the pulsing relay PR so as to initiate the homing of the switch S and the sending out of high voltage negative pulses in the usual manner to home the F switches. After this normal homing operation has been completed, the other nine parties on the line are now enabled to obtain service therefrom, but as regards the faulty party, it will be necessary for a maintenance officer to visit his premises and unlatch the relay before the service can be restored to him. Alternatively, it could be arranged that the relay PGR could be automatically unlatched as soon as the party replaced his receiver.

Considering now the arrangements for dealing with faults on the common party line, it is arranged that the party line stations will be isolated and that an alarm will be given in the case of a contact below a certain resistance value between the negative and positive conductors of

the party line, and of an earth fault below a certain resistance value on either conductor of the party line.

In the first case relay ST operates by way of its left-hand winding in a series with relay RF as in the case of the origination of a normal call and after the first pulse has been transmitted to line, in response to which all F switches will be stepped off-normal, a loop condition will still obtain on the party line, which condition only obtains in the case of contact between the party line conductors. Relay SZ will therefore operate to stop the pulse transmission in the usual manner and relay RF will be operated from earth, lower winding of relay SZ, armatures $c3$, $cr3$ and $sz1$, wiper $S5$ in position 2, key contacts KR1, left-hand winding of relay RF to battery. Relay RF at armature $rf1$ disconnects the left-hand winding of relay ST from the line in order to render ineffective the origination of calls by any of the party line subscribers, at armature $rf2$ completes a locking circuit for itself over its right-hand winding to earth via the release key contacts KR2, at armature $rf3$ completes a circuit to light the line fault lamp LFL, at armature $rf4$ applies earth to common lead 16 so as to set into operation suitable delayed alarm equipment which will give an alarm after a predetermined period, and at armature $rf5$ disconnects the incoming call circuit via relay IC.

In the case of a fault earth on the positive line, relay RF is directly operated over its right-hand winding and thereupon functions as already described, while in the case of a fault earth on the negative line no alarm is given until a call is originated when the loop placed across the line by the calling subscriber will allow relay RF to operate but relay ST will be unable to operate owing to the shunting effect of the fault earth on its left-hand winding.

After the line fault has been cleared, relay RF can be restored to normal by the operation of the release key RT whereupon at contacts KR1 and KR2 the circuits for both windings of relay RF are disconnected and this relay thereupon releases. If the equipment has been stepped off-normal it is then homed in the usual manner.

It will be understood that each of the various subscribers' stations on the party line could be provided with an indicator by means of which a visual busy indication could be given whenever the line was engaged. It will be further noted that the earthed switching equipment associated with each subscriber is connected to the positive line by way of neon tubes which in their non-conductive state during speaking conditions serve to isolate this equipment from the line thereby preventing the standard of speech transmission from being lowered.

In case the switch S in the exchange switch unit is accidentally stepped off-normal, it will be seen that a homing circuit to drive it to one or other of its two home positions 1 or 13 is completed via wiper and bank S1, armature $on2$, magnet interrupter contacts sm and magnet SM to battery.

I claim:

1. In a telephone system, a party line, each station on said line having certain equipment thereat normally disconnected from said line, a start circuit at each station over which calls from that station may be initiated, means responsive to the initiation of a call over the start circuit at any of said stations for connecting said equipment

at the calling station to said line without connecting said equipment at the others of said stations to said line, a device, means for at times operating said device over said line and the equipment at said calling station while said equipment is connected to said line, locking means associated with said device for thereafter maintaining the device operated, means operated after an interval for disconnecting said equipment at said calling station from said line, and means controlled by said device, if same was previously operated while said equipment was connected to said line, for disabling the start circuit at said calling station and maintaining the same disabled to prevent subsequent initiation of calls from that station.

2. In a telephone system, a party line, each station on said line having certain equipment thereat normally disconnected from said line, a start circuit at each station over which calls from that station may be initiated, means responsive to the initiation of a call over the start circuit at any of said stations for connecting said equipment at the calling station to said line without connecting said equipment at the others of said stations to said line, a device, means for at times operating said device over said line and the equipment at said calling station while said equipment is connected to said line, locking means associated with said device for thereafter maintaining the device operated, means for disabling the start circuits at all of said stations so long as said equipment at said calling station remains connected to said line, means operated after an interval for disconnecting said equipment at said calling station from said line and rendering said disabling means ineffective, and means controlled by said device if same was previously operated while said equipment at said calling station was connected to said line for thereafter maintaining the start circuit at said calling station disabled.

3. In a telephone system, an exchange, a party line outgoing from said exchange, each station on said line having a start circuit over which calls from that station may be initiated and also having another circuit normally disconnected from said line, a device at each station, means responsive to the initiation of a call over the start circuit at any station for connecting said other circuit at the calling station only to said line, thereby to render effective the device at said calling station only, means at the exchange thereafter operated for signalling over said line to operate said effective device, and means controlled by said device upon said operation to thereof disable said start circuit, thereby to prevent subsequent initiation of a call thereover.

4. In a telephone system, an exchange, a party line outgoing from said exchange, each station on said line having a start circuit over which calls from that station may be initiated and also having another circuit normally disconnected from said line, a device at each station, means responsive to the initiation of a call over the start circuit at any station for disabling all of said start circuits and connecting said other circuit at said calling station only to said line, said other circuit when connected to said line effective to render said device at the calling station only responsive to signalling current of a certain character applied to said line, means at the exchange thereafter operated to apply signalling currents of said certain character to said line to operate said responsive device, means controlled by said

device at said calling station upon said operation thereof to disable, independently of said first disabling means, said start circuit at said calling station only, and means at the exchange for thereafter controlling said first disabling means to re-enable the start circuits at all of said stations except said calling station.

5. In a telephone system, an exchange, a party line outgoing from said exchange, each station on said party line having a first circuit normally disconnected from said line, a start circuit at each station, a device at each station normally connected to said line over the start circuit thereat, means at each station for transmitting a signal to the exchange over the start circuit at that station when it is desired to extend a call, a switch at each station controlled from the exchange responsive to said signal for opening a point in the start circuit at that station, thereby to disconnect said devices from said line, said switch at the calling station only also controlled from the exchange to connect said device to the line over said first circuit at that station, means at the exchange for thereafter operating said device at the calling station over the line and said first circuit at the calling station, and means controlled by said device upon operation for opening another point in the start circuit at said calling station.

6. In a telephone system, an exchange, a party line outgoing from said exchange, each station on said party line having a first circuit normally disconnected from said line, a start circuit at each station, a device at each station normally connected to said line over the start circuit thereat, means at each station for transmitting a signal to the exchange over the start circuit at that station when it is desired to extend a call, a switch at each station controlled from the exchange responsive to said signal for opening a point in the start circuit at that station, thereby to disconnect said devices from said line, said switch at the calling station only also controlled from the exchange to connect said device to the line over said first circuit at that station, means at the exchange for thereafter operating said device at the calling station over the line and said first circuit at the calling station, means controlled by said device upon operation for opening another point in the start circuit at said calling station, and means in the exchange then operated for controlling said switches to close said first-named point in the start circuit at each of said stations.

7. In a telephone system, a party line, a plurality of stations on said line, means controlled from any station for extending a call over said line, a start circuit for said means including a portion at each station, means at each station for completing the start circuit portion at that station, means for then disabling the portions at all stations, means for thereafter enabling the start circuit portions, and means at each station controlled over said line to prevent the enabling of any one of said portions.

8. In a telephone system, a party line, each station on said line having certain equipment thereat normally disconnected from said line, means operable to cause the equipment at any selected station to be connected to said line, a start circuit at each of said stations for initiating the operation of said means, means for at times disabling said start circuits at all of said stations concurrently, and means operated at other times causing the start circuit at some one

of said stations to be disabled without causing the start circuits at the others of said stations to be disabled.

9. In a telephone system, a party line, each station on said line having certain equipment thereat normally disconnected from said line, means operable to cause the equipment at any selected station to be connected to said line, a start circuit at each of said stations for initiating the operation of said means, means for at times disabling said start circuits at all of said stations concurrently and, after an interval, for again enabling them, and means operated at times for preventing said enabling of the start circuit at some one station while permitting said enabling of the start circuits at all other stations.

10. In a telephone system, a party line extending to an exchange, a plurality of stations on said line, means at each station for initiating a call over said line and for locking out all other stations, and means controlled from the exchange over said line and operated whenever a certain station has initiated a call for locking out that particular station and restoring said locked out other stations.

11. In a system as claimed in claim 10, means under the control of the subscriber at said particular station for restoring that station after same has been locked out.

12. In a telephone system, a party line, three or more stations on said line each normally having access to said line for calls, means for associating any one of said stations with said line to permit that station to engage in a call and, during said call, barring the access of the others of said stations to said line, thereby to prevent said other stations from intruding upon said call, means for at times barring the access of said line of only one of said stations, when no other station on said line is engaged in a call.

13. In a telephone system, an exchange, a party line outgoing from said exchange, means at the exchange for transmitting particular train of impulses over said line to select different ones of said stations at different times, a switch at the exchange having a wiper operated step-by-step in synchronism with said impulses, and means controlled over said wiper of said switch for insuring that any particular one of said trains cannot be transmitted under certain conditions.

14. In a telephone system, an exchange, a party line outgoing from said exchange, a register at the exchange operated whenever any station or said line initiates a call, thereby to register the identity of the calling station, and means automatically controlled by said register for permitting calls to be extended over said line, when same is free, only from a predetermined one or more of said stations.

15. In a telephone system, an exchange, a party line outgoing from said exchange, a plurality of stations on said line, means at the exchange for transmitting impulses over said line to select different ones of said stations at different times, a circuit at the exchange including a different portion for each station on said line, a contact in each of said portions operable in different ways independently of the contacts in the others of said portions, a switch at the exchange operated in synchronism with said impulses for rendering the different ones of said portions of said circuit effective in turn, a device in said circuit effective when operated to halt said operation of said impulse transmitting means, and means for operating said device over said circuit.

cuit in any position of said switch only if the contact in the portion of said circuit effective in that position of said switch has been operated in a particular way.

16. In a telephone system, an exchange, a party line outgoing from the exchange, a switch at each station on said line, each of said switches having a normal position, means at the exchange for operating said switches in unison away from their respective normal positions, 10 means controlled by the switch at each station

for conditioning that station for a call only when said switch has been stepped to a predetermined off-normal position, the different stations being conditioned at different off-normal positions of the respective switches, and means at the exchange responsive to an abnormal condition on said line for causing said first means to operate said switches to an off-normal position in which no station on said line is conditioned for a call.
